CARPET.

No. 16,049.

Patented Apr. 14, 1885

UNITED STATES PATENT OFFICE.

MILTON R. LOUDON, OF JERSEY CITY, NEW JERSEY, ASSIGNOR TO THE BIGELOW CARPET COMPANY, OF CLINTON, MASSACHUSETTS.

DESIGN FOR A CARPET.

SPECIFICATION forming part of Design No. 16,049, dated April 14, 1885.

Application filed February 20, 1885. Term of patent 3½ years.

To all whom it may concern:
Be it known that I, MILTON R. LOUDON, a resident of Jersey City, in the county of Hudson and State of New Jersey, have invented and produced, by my own industry, genit's, efforts, and expense, a new and original Design for a Carpet, of which the following is a full description, in connection with the accompanying photograph, which represents a face view of my new design for a carpet.

This invention relates to a new ornamentation of the face of a carpet, oil-cloth, or analogous fabric.

In the accompanying photograph are represented the various parts which enter into my new design.

A is a fanciful leaf, to which is connected the fanciful leaf B, near which is a rosette, C. The figures A B C are near a stripe, D, of the carpet, which has cup-shaped ornaments 20 therein, near which is a stripe, E, having geometrical ornaments

I claim—

The design for a carpet, the same consisting of the figures A, B, C, D, and E, substantially 25 as shown.

MILTON R. LOUDON.
